UNITED STATES PATENT OFFICE.

OSKAR SCHWIDETZKY, OF NEW YORK, N. Y.

BOWLING GAME.

SPECIFICATION forming part of Letters Patent No. 718,391, dated January 13, 1903.

Application filed July 5, 1902. Serial No. 114,451. (No model.)

To all whom it may concern:

Be it known that I, OSKAR SCHWIDETZKY, a citizen of the Empire of Germany, residing in New York, borough of Manhattan, and 5 State of New York, have invented certain new and useful Improvements in Bowling Games, of which the following is a specification.

This invention relates to an improved bowling game of that class which is intended to 10 be played in the parlor or indoors, so as to form an amusement for grown people and children, the special improvement relating to the means for directing the barrel through which the ball is shot at the pins; and for 15 this purpose the invention consists in a bowling game comprising an inclined alley-board, a set of pins at the rear end of the same, a barrel at the front end of the board, and mechanism for directing the barrel in lateral and 20 upward direction prior to the shooting of the ball; and the invention consists, further, of certain details of construction and combinations of parts, which will be fully described hereinafter and finally pointed out in the 25 claims.

In the accompanying drawings, Figure 1 is a perspective view of my improved bowling game. Fig. 2 is a vertical longitudinal section of the barrel through which the ball is 30 shot, drawn on a larger scale and taken on line 2 2, Fig. 3; and Fig. 3 is a horizontal section on line 3 3, Fig. 2.

Similar letters of reference indicate corresponding parts.

35 Referring to the drawings, A indicates the casing of my improved bowling game. The casing A is made lower at the front end than at the rear end, the front end being covered by a closed top A'. In the casing A is arranged an inclined alley-board B, which is provided with pins P at its rear end, the top of the casing above the alley-board B being closed by a glass pane, which exhibits the pins, but prevents access to the same. The 40 pins may be overturned by the ball by any approved mechanism, which is not shown. At the front end of the inclined alley-board B and centrally to the same is arranged a barrel C, which is held in position by two 45 springs D, that are attached to the alley-board B and extend from the side walls of the casing inwardly alongside of the barrel C,

so that their free ends act on both sides of the same. The curved springs D serve also as abutments for returning the ball into the 55 barrel after each throw. The front end of the barrel is located in a recess of a partition-wall A², that separates the front part of the casing from the main portion of the same. The ball is shot from the barrel by the ful- 60 crumed and spring - actuated hammer by means of any suitable actuating mechanism, the hammer being shown in dotted lines in Fig. 2. The front end of the barrel is connected by a fulcrumed pin f with a lever F, 65 which is pivoted to said fulcrumed pin at its front end and fulcrumed on a transverse support g, the ends of which are pivoted to lugs g', attached to the partition-wall A², as shown clearly in Fig. 3. The rear end of the lever 70 F is provided with a bent-up centrally-recessed lug f', which is engaged by the forwardly-bent end e at the lower end of a shank e', that passes through the top of the casing to the outside of the same, where an operating-button E is applied thereto. The pivoted support g of the lever F is connected by a helical spring s with a fixed point on the transverse partition A², said spring serving 80 to return the barrel into its normal position 85 of rest on the alley-board after the same has been raised by depressing the button E. On the partition-wall A², above the front end of the barrel C, is arranged a transverse bar h, which serves as a stop for the pin f of the 85 barrel when the same is moved in upward direction, while the lateral movement of the barrel is controlled by the side springs D, which serve to return the same into normal position. 90

The operation of my improved bowling game is as follows: The hammer by which the ball is shot through the barrel is actuated by any suitable actuating device, which may be coin-operated or otherwise, so that the ball 95 is thrown through the barrel against the pins. Before the ball is shot by the hammer-operating mechanism the barrel is placed into proper position by depressing the button and moving the same in either direction. The 100 depression of the button produces the slight lifting of the barrel at different angles of inclination to the alley - board, as shown in dotted lines in Fig. 2. Simultaneously the

barrel may be moved on its pivot-pin to one side or the other by turning the button in the direction desired, so as to force the retaining-spring to one side, as shown in Fig. 3, said 5 spring always returning the barrel to centrally normal position after the pressure on the button is released. The spring acting on the pivoted supporting-bar *g* of the directing-lever *F* also serves for returning the barrel 10 into position on the alley-board after the lifting action produced by depressing the button has been released. The intermediate mechanism by which the barrel is connected with the directing-button serves, therefore, 15 for the double purpose of changing the inclination of the barrel and moving it slightly to one side or the other, as required, to direct the ball at the pins still standing after the previous shots. In this manner the barrel 20 can be directed after some practice so as to shoot the ball with the best possible effect either when all the pins are standing or when some are standing, the directing of the barrel requiring some skill, whereby the pleasure 25 and interest in the game is increased.

Any suitable setting-up mechanism for the pins is used in connection with the game; but the same is not here shown, as being beyond the scope of my invention.

30 Having thus described my invention, I claim as new and desire to secure by Letters Patent—

1. In a parlor bowling game, the combination, with an inclined alley-board, of a set of pins at the rear end of the same, a barrel at 35 the front end of the board, said barrel being pivoted at its front end, curved springs attached to the alley-board and placed in con-

tact with the opposite sides of the barrel, said curved springs serving as abutments for returning the ball to the barrel, substantially as set forth. 40

2. In a parlor bowling game, the combination, with an inclined alley-board, of a set of pins at the rear end of the same, a barrel at 45 the front end of the board, curved springs extending from the sides of the alley-board to opposite sides of said barrel, the curves of said springs forming abutments for returning the ball, and means for directing the ball 50 in vertical as well as lateral direction, substantially as set forth.

3. In a parlor bowling game, the combination, with an inclined alley-board provided with a set of pins at one end, of a barrel for 55 shooting at the opposite end, cushioning-springs arranged at opposite sides of said barrel and curved toward the sides of the alley-board, said springs serving as abutments for returning the ball to the barrel, a fulcrumed 60 and spring-actuated lever engaging the barrel at its front end, a pivoted and spring-actuated support for said lever, and a shank engaging the rear end of said lever, said shank being provided with a button for moving 65 the lever in upward or downward or lateral direction for directing the barrel prior to shooting the ball, substantially as set forth.

In testimony that I claim the foregoing as my invention I have signed my name in presence of two subscribing witnesses. 70

OSKAR SCHWIDETZKY.
